UNITED STATES PATENT OFFICE.

FREDERICK L. BRIGHAM, OF UPPER MONTCLAIR, NEW JERSEY.

FABRIC AND METHOD OF MAKING THE SAME.

Application filed September 4, 1925. Serial No. 54,406.

To all whom it may concern:

Be it known that I, FREDERICK L. BRIGHAM, a citizen of the United States, and a resident of Upper Montclair, in the county of Essex and State of New Jersey, have invented certain new and useful Improvements in Fabrics and Methods of Making the Same, of which the following is a specification.

10 My invention is directed to an improvement in elastic fabrics and to the thread from which the fabric is made, as well as to the method of making the fabric and thread.

In the manufacture of elastic fabrics as now practised with particular reference to woven elastic fabrics, it is customary to employ warp threads comprising an elastic core or strand enclosed in one or more fibrous coverings, such as cotton or silk for example, usually wrapped spirally about the core while the elastic core thread is stretched to its approximate limit. In the weaving of such fabrics the warp threads are extended to the approximate limit of the elastic of the core thread, and if a short stretch fabric is desired, either the filler threads in the process of weaving are beaten up as tight as is practicable or starch is used in order to control the stretch of the finished fabric.

30 When such a fabric is made up into a garment, however, it is not feasible to cut the fabric along the selvage edge or edges thereof to shape the garment, inasmuch as this releases the rubber cores of the warp threads and the same pull back through the fabric to cause "runs" therein. The use of starch is also a disadvantage inasmuch as when such material is washed or becomes damp the starch is dissolved out so that any benefit 40 which may have been derived from the presence of the starch in the fabric is lost.

My invention provides a process whereby an improved fabric is produced wherein, if the elastic core of the warp threads be cut from any cause, either from stitching stays in place or in cutting the fabric along the selvage edge, for example, these severed threads will remain in position, i. e., will not pull back through the fabric.

50 My improved fabric is also of such a character that the results desired may be obtained without the necessity of employing starch or without any abnormal beating up of the filler threads to control the stretch of the fabric, and without stretching the elastic core threads to a detrimental extent.

Briefly, my invention provides a fabric in which an improved thread is employed comprising an elastic thread or threads and a non-extensible thread or threads twisted together and covered with a covering of non-extensible material. This fabric may be cut along the selvage edge thereof and stays, hose supporters and the like stitched to the fabric in the making of a garment therefrom without the extensible thread of the cores pulling back.

In incorporating my improved thread into a fabric the non-extensible stay threads prevent extension of the extensible core threads beyond a certain predetermined limit, thereby enabling the stretch of the finished material to be controlled, this feature of my invention being accomplished as above noted without the necessity of employing starch and without the necessity of any abnormal beating up of the filler threads.

Other and further advantages of my invention will appear hereinafter.

In the accompanying drawings wherein I have illustrated an embodiment of my invention, Fig. 1 is a plan view of one form of my improved fabric employing my improved thread;

Fig. 2 is a more or less fragmentary view 85 of my improved thread in the first stages of its manufacture;

Fig. 3 shows the thread in its more advanced state of manufacture showing the covering threads being applied thereto;

Fig. 4 shows the completed thread in elevation; while

Fig. 5 is a section through the thread of Fig. 4.

Referring to the drawings in detail, 1 designates a section of extensible material, such as elastic for example, which constitutes a part of the core of my improved thread. 2 is a section of non-extensible material such as cotton, for example, this 100 thread hereinafter being referred to as a stay thread. The elastic thread 1, which I will refer to as a core thread, and the stay thread 2 are twisted together as indicated in Figs. 3 and 4 by any suitable twisting machine, of which there are several well known in the art. In the twisting together of these two threads the core thread 1 is extended, but not beyond its elastic limit, the extension of the core thread being limited by the 105 stay thread. After the stay and core threads have been twisted together I wrap

a covering or binding thread 3, and if desired a thread 4, about the twisted threads 1 and 2, a section of my finished thread being shown in Fig. 4. The threads 3 and 4 are of non-extensible material such as cotton, silk, etc., and are wound about the threads 1 and 2 spirally, one thread being wound right hand, while the other is preferably wound in the opposite hand. This method, therefore, produces a thread comprising an elastic core thread 1 and a non-extensible stay thread 2 twisted together and covered with a non-extensible covering or binding thread 3 and an additional covering or binding thread 4. My improved thread is of such a character that even though the elastic or extensible thread 1 be cut, the same will not pull back or retract through the coverings 3 and 4. This characteristic is due to the core thread 1 and non-extensible stay thread 2 being twisted together but is no doubt aided to a considerable extent by the application of the covering or binding threads 3 and 4.

I may here mention that while I have illustrated and described but one elastic core thread and one non-extensible stay thread, it is to be understood that I may employ a plurality of both or either such threads.

In making up my improved thread into an elastic fabric, I employ my improved thread for the warp when making a woven fabric, and for clarity this thread has been designated 5 in Fig. 1, preferably in conjunction with fibrous binder threads 6 and gut threads 7, these threads being cotton, silk, or other suitable material, thus producing a fabric of interlaced threads. The gut threads employed may consist of any suitable number, four for example, as illustrated.

In the weaving of this fabric the core threads 1 are placed under tension to the approximate limit permitted by the non-extensible stay threads 2, it being understood, of course, that the fibrous binder and gut threads above referred to are also under some tension. With the threads in the condition first indicated, the fabric may be woven in the usual way. I have found that a fabric in which twenty or twenty-one of my improved warp threads are employed to the inch and in which thirty-two ply yarn for the gut and sixty-two ply yarn for the binder threads are employed produces a satisfactory fabric.

By the employment of my improved method of making a thread and by employing this improved thread in the making up of a fabric, the elastic core thread 1 being stretched to the limit permitted by the inextensible stay thread 6, a short stretch fabric is produced without employing starch or any abnormal beating up of the filler threads.

If desired, however, a small percentage of starch or other material may be used in the finishing process to give body and smoothness to the finished fabric.

I find also that a fabric produced in accordance with this invention and employing the improved thread above described may be cut along the selvage edge as indicated in broken lines at 8 in Fig. 1 without the elastic or extensible threads 1 pulling back through the fabric and causing "runs."

It is to be understood that the improved thread of this application may be employed in making up fabrics other than woven fabrics within the purview of my invention.

What I claim is:—

1. An article of manufacture comprising an elastic thread and a non-extensible thread twisted together and a covering spirally wrapped about said threads.

2. An article of manufacture comprising an elastic thread and a non-extensible thread twisted together and a covering of non-extensible material spirally wrapped about the said first-mentioned threads.

3. An article of manufacture comprising an elastic thread and a non-extensible thread twisted together continuously, and a covering of non-extensible material spirally wrapped about said threads.

4. An article of manufacture comprising an elastic thread and a non-extensible thread twisted together, and a non-extensible thread wrapped about the two first-mentioned threads.

5. An article of manufacture comprising an elastic core thread and a non-extensible stay thread of a length to limit the extension of the said extensible core thread, said threads being twisted together, and a non-extensible thread wrapped about the two first-mentioned twisted threads.

6. A woven fabric some of the warp threads of which comprise a core composed of an elastic thread and an inelastic thread twisted together and covered with a non-elastic thread wrapped about them.

7. A fabric comprising a plurality of interlaced threads, some of said threads comprising an elastic core thread and a non-elastic stay thread twisted together, and covered with a non-elastic thread wrapped about them.

8. The method which consists in twisting an elastic thread and a non-extensible thread together and applying a covering spirally about said threads.

9. The method which consists in twisting an elastic thread and a non-extensible thread together and wrapping a non-extensible thread about the two twisted-together threads.

10. The method of manufacturing elastic fabric which method consists in employing warp threads provided with a core comprising

ing an elastic thread and a non-elastic thread twisted together and a cover spirally wrapped about said core, and weaving the fabric with the warp threads under the tension permitted by the non-elastic thread of the warp thread core.

11. The method which consists in twisting an elastic thread and a non-extensible thread

together with the elastic thread under tension, and then winding a covering thread of non-extensible material about the said first-mentioned threads with the elastic thread under tension.

This specification signed this 2nd day of September, 1925.

FREDERICK L. BRIGHAM.
